BULLDOZER CONSTRUCTION

Harold Sorensen, Knappa, Oreg.

Application May 6, 1940, Serial No. 333,563

4 Claims. (Cl. 37—144)

My invention relates broadly to apparatus employed for handling earth and analogous materials in road and trail building and clearing. The invention has particular relation to scraper or bulldozer blades and supporting frames therefor employed in conjunction with and supported by a tractor or similar vehicle for bulldozing, scraping, side casting, leveling, back filling, and a variety of other operations and functions required in the building and clearing of roads and trails.

A fingernail sketch of the features of the invention and an explanation of its functions with particular stress of its importance in logging operations is deemed advisable at this time. The present structural characteristics of scraper or bulldozer blades and supporting frames therefor employed to perform the foregoing operations and functions admittedly perform the work with some modicum of efficiency; but the tractor and the bulldozer tend to be deflected and this causes strain and excessive wear on both of them when a single unit blade is employed to perform these various functions. It has been found advantageous to provide a scraper or bulldozer blade made of two sections so that it may be adjusted to a number of different positions in the horizontal plane to perform these various tasks without causing deflection and undue stress and wear on the tractor or the bulldozer. However, investigation has failed to disclose any bulldozers having scraper or bulldozer blades and supporting frames therefor which permit the folding of the blades against the sides of the tractor or similar vehicle into a compact and convenient position when not in use.

Existing scraper or bulldozer blades normally extend for some distance beyond the sides of the tractor or similar vehicle with which they are associated. The massiveness of the bulldozer and the extension of the blades beyond the sides of the tractor interfere with the use of the tractor or similar vehicle for other work. It is at present necessary to remove the scraper or bulldozer blade and supporting frame therefor, when it is desired to use the tractor or similar vehicle for work not connected with trail or road building or clearing. Because of the type of work which bulldozers are required to perform, they are bulky and exceedingly heavy; and to remove the scraper or bulldozer blades and supporting frame therefor from the tractor or similar vehicle entails considerable loss of time and effort and creates additional expense for labor; and a like loss of time, effort and expense is entailed, when

it is desired to mount the bulldozer frame and blade onto the tractor or similar vehicle.

In addition to the above disadvantages inherent in scraper or bulldozer blades and supporting frames therefor, there is the disadvantage resulting from the lack of versatility of the scraper or bulldozer blades in performing the several functions ordinarily required to be performed in the building and clearing of roads and trails.

These foregoing disadvantages are magnified particularly in logging operations, where it is desired to employ a tractor or similar vehicle and a scraper or bulldozer blade and supporting frame therefor. It is often necessary to build or clear roads and trails in order to bring logs out of the logging area. It is therefore essential that a scraper or bulldozer blade and supporting frame therefor be carried at all times by the tractor or other vehicle which normally pulls a log carrier. Because of the narrowness of the roads in logging areas, the numerous sharp curves and other obstructions, such as stumps and trees lining the side of the logging roads, it is necessary to maintain the scraper or bulldozer blades and supporting frame therefor as closely as possible to the sides of the tractor. It is, therefore, within the contemplation of my invention to provide a scraper or bulldozer blade having such structural characteristics as will permit a more versatile angular adjustment thereof so that it will be possible not only to cast on either side or to carry the load forward and to perform a variety of similar functions, but also to provide a blade which may be positioned, when not in use, against the sides of the tractor, and which overcomes the disadvantages inherent in the present type of scraper or bulldozer blade construction.

The salient feature of my invention is to provide a scraper or bulldozer blade which can be readily adjusted to numerous angular positions in order to perform a variety of operations for the building and clearing of roads and trails and which can be folded against the sides of the vehicle to which the blade-carrying frame is attached, when the blade is not in use and during transit of the vehicle from place to place.

It is an object of my invention to provide a scraper or bulldozer blade which is adapted for scraping, bulldozing, double and single side casting, leveling, back filling, and a variety of other operations presently performed by a number of single job-performing devices.

An equally important object of my invention is to provide a blade-carrying frame secured to

and adjustably positionable with respect to a tractor or similar vehicle which permits not only of its being raised, lowered or tilted relative to the tractor or similar vehicle, but also of the variable angular adjustment of its blade.

Still another object of my invention is to provide a scraper or bulldozer blade consisting of a plurality of sections which may readily be folded against the side of the tractor or vehicle with which it is associated, when further use of the blade is not desired or when the tractor is in transit, or which may be extended beyond the tractor sides, when in operative position, and set at almost any acute or obtuse angle desired by the operator.

A further object of the invention is to provide a scraper or bulldozer blade and a supporting frame therefor, the construction of which is simple enough to allow one operator to make the desired adjustments of the frame relative to the tractor and of the blade relative to the frame under all conditions which may be encountered by the operator.

Still another object of my invention is to provide means for firmly holding the blade sections in their adjusted position to insure against variance in the depth and angle of cut during the operation.

Still another object of the invention is to provide a scraper or bulldozer blade and a supporting frame therefor which is adapted to perform an extensive range of functions, which is rugged in construction, easy to handle, inexpensive to manufacture and maintain, which reduces need for single job-performing implements, and which overcomes the disadvantages inherent in the present type of scraper or bulldozer blade construction.

The foregoing and other related objects are attainable by the bulldozer construction illustrated in the accompanying drawings which show but one embodiment by which the invention may be realized and which must be examined with reference to the following detailed descriptions. In the accompanying drawings, in which the same reference characters are employed throughout the several views to designate the same elements:

Figure 1 is a side view of the scraper or bulldozer blade and blade-supporting frame embodying the principles of my invention, showing their positions relative to a tractor and a log carrier, both fancifully represented and shown in dotted line;

Figure 2 is a plan or top view of the scraper or bulldozer blade and supporting frame therefor, showing the position of the blade, when the blade sections are in the same transverse plane ready for straight bulldozer work;

Figure 3 is a fragment of a side beam and a channel arm, showing the structural characteristics thereof and the means employed for disengageably connecting the two;

Figure 4 is a fragmentary elevation, partly in section, taken on line 4-4 of Figure 2, looking in the direction indicated, showing the means employed for joining the wing blade sections to the central blade section;

Figure 5 is a plan or top view of the scraper or bulldozer blade and supporting frame therefor, illustrating the position of the various blade sections to perform left side casting.

Figure 6 is a plan or top view of the scraper or bulldozer blade and supporting frame therefor, illustrating the position of the various blade

sections to form a pocket for accumulating and carrying material forward, commonly called "drifting;" and

Figure 7 is a plan or top view of the scraper or bulldozer blade and supporting frame therefor, illustrating the position of the various blade sections when being used for casting to both sides, or when the blade sections are folded against the sides when the bulldozer is not in use and the vehicle is in transit, or is used for 10 other type of work.

In Figure 1 a tractor is fancifully represented and shown in dotted line and, since it is no part of the invention, except as the support for the blade-supporting frame, will be broadly designated by reference character A for the purposes of the following description. Also fancifully represented and shown in dotted line is a log carrier whose structural characteristics are no part of the invention and which, therefore, will be 20 generally designated by reference character B for the purposes of the following description.

The broad structural characteristics of the invention may best be seen in Figure 2 which shows a blade-supporting frame, designated generally by reference character C. This frame consists of side beams 1 and 2 positioned on each side of the tractor A with their ends 3 and 4 respectively positioned on the stub shafts 5 and 6 extending outwardly from the sides of the tractor A, thus forming a movable joint between the beams and the tractor, so that the frame may be raised or lowered relative to the tractor as the occasion demands. The stub shafts are securely and rigidly held to the sides of the tractor and are adapted to resist the rearward thrust occasioned by the work performed by the bulldozer. The raising and lowering of the frame may be accomplished by any means, such as, for purposes of illustration, a cable 7 which is 40 secured to an eye 8 connected to the frame C.

Secured to or made an integral part of beam 1 is an inwardly and forwardly inclined beam extension 9. A similarly inclined beam extension 10 is secured to or made an integral part of 45 beam 2. Both of these beam extensions connect to or are integrally joined to a transversely positioned cross or front beam or "nose" portion 11. These variously described elements form approximately the U-shaped frame C which carries 50 the blade, hereafter to be described. The U-shaped frame C is ruggedly constructed and adequately reinforced to withstand the rearward thrust caused by the action of the blade. Openings 12, 13 and 14 extend through beam 1. Similar openings 15, 16 and 17 are formed through beam 2. These openings are respectively aligned with each other and are employed for the function shortly to be set out.

The scraper or bulldozer blade, designated broadly by reference character D, is divided into a plurality of sections 18, 19 and 20. The working faces of each of the blade sections, all exemplified by reference character 21, may be concave as shown in Figure 1, or may have an inclined or straight face, whichever shape suits the wishes of the manufacturer or user. The wing blade sections 18 and 20 possess substantially the same structural characteristics and 70 are of the same width. The central blade section 19, while possessing substantially the same structural characteristics as wing blade sections 18 and 20, is of a width equal to the width of the transverse front beam 11. The central blade 75

section 19 is secured to and is reinforced by front beam 11, while wing blade sections 18 and 20 have reinforcing ribs 22 and 23 respectively secured to the backs thereof. Wing blade sections 18 and 20 are each movably secured to member 11, so that they may be moved forwardly or rearwardly. The types of hinge employed is best illustrated in Figure 4 which shows a pair of ears 24 and 25 extended in spaced parallel relation to each other at one end of the reinforcing bar 23. An opening (not shown) is formed adjacent and through the end 26 of front beam 11. Ears 24 and 25 fit over the end 26 of member 11, so that the openings (not shown) in the ears 15 are in direct alignment with the opening (not shown) in the cross beam 11. A pin 27 passes through the openings (not shown) and is secured therein against unauthorized removal. An identical hinge connection is provided for wing blade section 18 which itself is hinged in the same manner to the end 28 of front beam 11.

Channel arms 29 and 30 are removably secured to wing blade sections 18 and 20 respectively and fit over and are slidably positioned 25 and secured to beams 2 and 1 respectively. This is accomplished by providing at one end of the arm 29 a pair of ears 31 and 32 and a similar pair of ears at one end of the arm 30. An opening (not shown) is formed through and adjacent the end 33 of wing blade section 18 and a similar opening (not shown) is formed through and adjacent the end 34 of wing blade section 20. The ears 31 and 32 fit over the reinforcing bars 22 and 23, so that the openings (not shown) in the ears 31 and 32 are in alignment with the openings (not shown) in the respective ends 33 and 34 of reinforcing bars 22 and 23. Pins 35 and 36 join the arms 29 and 30 respectively to wing blade sections 18 and 20 respectively.

The other end of each of the arms 29 and 30 are also provided with identical pairs of ears 37 which fit over the beams 1 and 2. Openings (not shown) are formed through the pairs of ears 37 and these may be aligned with any of the openings 12, 13 and 14 formed in beam 1 and openings 15, 16 and 17 formed in beam 2, depending upon the position which the wing blade sections 18 and 20 are to assume. If the openings in the pairs of ears 37 are aligned with openings 13 and 16, the wing sections 18 and 20 will assume the position shown in Figure 2; if the openings in the pairs of ears 37 are aligned with openings 12 and 17, the wing blade sections 18 and 20 will assume the position shown in Figure 5; if the openings in the pairs of ears 37 are aligned with openings 12 and 15, these wing blade sections will assume the position shown in Figure 6; and if the openings in the pairs of ears 37 are aligned with openings 14 and 17, the wing blade sections will assume the position shown in Figure 7. Once the position of the wing blade sections have been determined, the arms 29 and 30 are locked against beams 2 and 1 respectively by means of the pins 38 and 39, best exemplified in Figure 3. In this manner the arms are secured to the beams and the wing sections are held in fixed position.

The positions which the wing sections 18 and 20 assume with respect to each other and to the central blade section 19 are controllable only by the number of openings formed in the beams 1 and 2 which, in the drawings, are shown as three in number for each beam.

It should be pointed out that, when a bulldozer embodying the foregoing construction is attached

to a tractor which is engaged in arch logging, it possesses more effective maneuverability in close quarters. Furthermore, a scraper or bulldozer blade and supporting frame therefor of the type illustrated and described is admirably adapted to clear paths for the tractor without creating too heavy a load on the tractor itself, since its primary function is to remove logs from the logging area. When the blades are positioned as shown in Figure 7, they are helpful in acting as a wedge for the tractor in its travel through areas where logs are lying too close together and also assists in steering the tractor away from obstructions, since the folded wings would not become snagged in stumps and other obstructive matter normally found in logging areas.

From the foregoing description, it will undoubtedly appear that the invention as described satisfies the objects and points out the advantages claimed for this invention. While the invention has been described in connection with a specific embodiment, it should be understood that variants thereof are possible to those skilled in the art. The invention, therefore, in its broader aspect, is not limited to the specific construction herein shown and described, since changes and alterations may be made in the proportions and arrangements of the various parts without departing from the spirit of the invention.

Having thus described my invention, what I claim as new and upon which I desire to secure Letters Patent is:

1. In a device of the class described including a tractor or similar vehicle, an approximately U-shaped frame pivotally connected to said tractor or similar vehicle, said frame comprising a pair of side beams disposed on each side of the vehicle and extending forwardly thereof, inwardly and forwardly inclined beam extensions joined to said beams and a transverse front beam joining said beam extensions to each other, a scraper or bulldozer blade connected to said frame, said blade comprising a central section secured to the transverse front beam and a pair of wing sections hingedly secured to said transverse front beam and positioned on each end of said central section, said wing sections being so hinged to said transverse front beam that they may be swung forwardly or rearwardly independent of each other, and means secured to said wing sections and positionable upon the side beams of said frame adapted to control the position of each of said wing sections relative to the frame and to the central section of said blade.

2. In a device of the class described including a tractor or similar vehicle, an approximately U-shaped frame pivotally connected to said tractor or similar vehicle, said frame comprising a pair of side beams disposed on each side of the vehicle and extending forwardly thereof, inwardly and forwardly inclined beam extensions joined to said beams and a transverse front beam joining said beam extensions to each other, a scraper or bulldozer blade connected to said frame, said blade comprising a central section secured to the transverse front beam and a pair of wing sections hingedly secured to said transverse front beam and positioned on each end of said central section, said wing sections being so hinged to said transverse front beam that they may be swung forwardly or rearwardly independent of each other, and channel arms secured to said wing sections, said arms having sliding, adjustable connection with the side beams of said frame whereby the wing sections of said blade may be

adjusted to a plurality of working positions.

3. In a device of the class described including a tractor or similar vehicle, an approximately U-shaped frame pivotally connected to said tractor or similar vehicle, said frame comprising a pair of side beams disposed on each side of the vehicle and extending forwardly thereof, inwardly and forwardly inclined beam extensions joined to said beams and a transverse front beam joining said beam extensions to each other, a scraper or bulldozer blade connected to said frame, said blade comprising a central section secured to the transverse front beam and a pair of wing sections hingedly secured to said transverse front beam 10 and positioned on each end of said central section, said wing sections being so hinged to said transverse front beam that they may be swung forwardly or rearwardly independent of each other, means secured to said wing sections and 15 positionable upon the side beams of said frame adapted to control the position of each of said wing sections relative to the frame and to the central section of said blade, and means for locking said first-mentioned means to said frame 20 adapted to rigidly hold said wing sections at the predetermined positions.

4. In a device of the class described including

a tractor or similar vehicle, an approximately U-shaped frame pivotally connected to said tractor or similar vehicle, said frame comprising a pair of side beams disposed on each side of the vehicle and extending forwardly thereof, inwardly and forwardly inclined beam extensions joined to said beams and a transverse front beam joining said beam extensions to each other, a scraper or bulldozer blade connected to said frame, said blade comprising a central section secured to the transverse front beam and a pair of wing sections hingedly secured to said transverse front beam and positioned on each end of said central section, said wing sections being so hinged to said transverse front beam that they may be swung forwardly or rearwardly independent of each other, channel arms secured to said wing sections, said arms having sliding, adjustable connection with the side beams of said frames whereby the wing sections of said blade may be adjusted to a plurality of working positions, and means for adjustably securing said channel arms to the side beams of said frame adapted to rigidly hold said wing sections in any one of the plurality of working predetermined positions. 25

HAROLD SORENSEN.
